Primary Examiner — Susan Bennett Hattan*Assistant Examiner* — Brett Miller(74) *Attorney, Agent, or Firm* — Sterne, Kessler,
Goldstein & Fox P.L.L.C.(57) **CLAIM**

The ornamental design for a mount, as shown and described.

DESCRIPTION

FIG. 1 is a top front perspective view of a mount showing the claimed design;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof; and,

FIG. 8 is a top front perspective view thereof showing the mount in an environment in which it may be used.

The broken lines in the figures show portions of the mount or environment that form no part of the claimed design.

1 Claim, 5 Drawing Sheets(56)
